Inventor:

James Livesey Scott
By *True Name* (Signature)
Attorney.

UNITED STATES PATENT OFFICE.

JAMES L. SCOTT, OF MELBOURNE, VICTORIA, AUSTRALIA.

MECHANISM FOR AUTOMATICALLY REWINDING THE MUSIC ROLLS OF PLAYER PIANOS
AND THE LIKE.

Application filed March 6, 1922. Serial No. 541,488.

To all whom it may concern:

Be it known that I, JAMES LIVESEY SCOTT, a subject of the King of Great Britain and Ireland, and a resident of the postal district 5 of Sunshine, in the shire of Braybrook, a suburb of the city of Melbourne, in the county of Bourke, State of Victoria, Commonwealth of Australia, have invented a certain new and useful Improved Mechanism for Automatically Rewinding the Music Rolls of Player Pianos and the like, of which the following is a specification.

This invention relates to player pianos and like instruments and its object is to provide a simple, inexpensive and reliable mechanism for automatically rewinding the perforated music rolls or records of such apparatus after playing, thereby eliminating the usual slow and arduous task of rewinding by operation of the foot pedals. In addition the invention has the distinct advantage of being readily applicable to existing as well as to new types of instruments.

Referring to the drawings which form 25 part of this specification:—

Figure 1 is a front view showing the invention applied to a player piano.

Figure 2 is an enlarged cross sectional view of the governor.

Figure 3 is an enlarged side view looking in the direction of the arrow in Figure 1. The parts are shown in their normal position with the moving limit stop on the slotted stop wheel engaging the left hand side of 30 the co-operating stationary stop or bracket.

Figure 4 is a cross section on line A—A of Figure 1 looking in the same direction as Figure 3.

Figure 5 is an enlarged detail view of the 40 stop wheel shown in Figures 1 and 3.

Figure 6 is a detail view of a modification in which a weight is employed in lieu of a spring to automatically rewind the music roll.

Figure 7 is a front view of Figure 6.

The invention includes a suitable framework preferably of wood and comprising a horizontal member or board 2 from which depends a pair of opposite legs 3 adapted 50 to rest upon the usual uprights 4 at each side of the tracker bar 6. The invention may be thus readily placed in position within the upper part of the instrument and removed therefrom when desired.

Mounted in suitable brackets or bearings 55 5 and 7 on said frame is a shaft 8 on one end of which is a sprocket wheel 9 driven by a sprocket chain 11 from the usual sprocket wheel 12 on the roll spindle 13 to which the perforated music roll 10 is detachably connected in conventional manner. A jockey pulley 14 may bear against said sprocket chain which takes the place of the usual rewinding chain connecting the sprocket wheel 9 with the driving sprocket 15. The 60 latter is mounted in the usual manner on the driving shaft 16 which carries the pinion 18 and clutch 19 whereby the receiving spool 21 and the roll spindle 13 may be alternately rotated in opposite directions to respectively 65 unwind and rewind the music roll or sheet by the operation of the foot pedals.

A fan blade or blades 22 are preferably attached to the shaft 8 to act as a governor for retarding the automatic rewinding of the 70 roll as hereinafter described.

Connected by a train of reduction gears 23 with the shaft 8 is a shaft 24 which is mounted in the bearings or brackets 5 and 26 depending from the horizontal member 2 of 80 the supporting frame. Connected to the shaft 24 is one end of a clock spring 27 the other end of which is secured to a suitable projection 28 from the frame so that as the shaft 8 is rotated through its sprocket wheel 9 and chain 11 by the operation of unwinding or playing the music roll, the spring shaft 24 is also rotated at a greatly reduced speed and the spring is wound up.

Carried by the spring shaft 24 is a stop 90 wheel. This wheel preferably comprises two opposite discs 29 spaced from each other upon the spring shaft as in Figures 1 and 5 and provided with one or more opposite arcuate slotways 31. One of these slotways 95 freely accommodates a moving limit stop in the form of a cross pin 32 which extends between the two discs and is adapted to engage a co-operating stationary member or stop which may consist of the bracket 26 on 100 which the shaft 24 is mounted. By reason of this stop mechanism the spring 27 is prevented from becoming completely unwound or run down owing to the engagement of the stop 32 with the left hand side of the stop 26 as in Figure 3 when the parts are in normal position and the rewinding of the roll has been completed. Thus the spring has 105

always a reserve of power to overcome frictional resistance and completely rewind rolls of all sizes.

By means of the arcuate slot the stop wheel is permitted to over-run its moving stop 32 after the latter strikes the right hand side of the co-operating stationary stop or bracket 26 in Figure 3 with the result that the spring 27 may be wound up and consequently unwound to a greater extent for comparatively long music rolls.

In a modification as illustrated in Figures 6 and 7 the spring 27 may be dispensed with and in lieu thereof a weight 33 is attached to a line or cord 34 passing over a pulley 36 which constitutes the stop wheel and takes the place of the slotted discs above mentioned. A series of circumferentially spaced adjusting holes 37 may be formed through the side of said pulley to accommodate in the desired position, the aforesaid moving limit stop or pin 32 which thus outstands from the pulley and is adapted to engage the stationary stop or bracket 26 to arrest the rotation of the stop wheel and consequently limit the winding up of the weight line so that the weight will not foul the pulley. It will be evident that with this arrangement also the stop wheel or pulley 36 may be circumferentially slotted to permit it to overrun the stop 32 and thus lift the weight further for longer rolls whilst at the same time preventing the weight fouling the pulley.

In operation the unwinding or playing of the music roll 10 causes the spring or the weight line to be slowly wound up by the slow rotation of the shaft 24 until the moving stop 32 on said wheel strikes the co-operating stationary stop 26 and thus arrests the rotation of the wheel and the winding up of the spring or weight line. By the provision of the slots 31 in the stop wheel or pulley as before mentioned said wheel is permitted to over-run its limit stop or pin 32 after the latter has engaged the co-operating stationary stop 26 on the winding up of the spring or weight line and unwinding of the music roll. The stop wheel is thus permitted to turn to a greater extent or beyond the limits circumscribed by the engagement of the moving limit stop thereon with the co-operating stationary stop. The winding and unwinding of the spring or the weight line may be thus increased to complete the rewinding of comparatively long music rolls.

To rewind the roll 10 it is merely necessary to move the usual hand lever which operates the clutch 19 and disengages the driving gear 18 of the receiving spool 21 by which the music roll is unwound. This spool is thus released to run freely and the tension on the music roll is consequently released so that the unwinding of the spring

or the weight line will automatically rotate the roll spindle 13 to rewind the music roll or note sheet onto its reel or spool which may be then removed in the usual manner. The unwinding of the spring is limited as aforesaid by the stop mechanism so that the power of the spring is never fully expended. In the case of the weight controlled apparatus it will be evident that the stop mechanism is used primarily to limit the rising rather than the falling of the weight which naturally retains its full power.

It will be obvious that various alterations or modifications may be introduced into the particular construction described and illustrated without departing from the spirit and scope of the invention.

Having now described my invention what I claim as new and desire to secure by Letters Patent is:—

1. Improved mechanism for automatically rewinding the music rolls of player pianos and the like, consisting in the combination of a framework removably mounted in the upper part of the instrument, a shaft carried by said framework, means for operatively connecting said shaft with the music roll spindle, a reduction gear carried by the framework and adapted to be driven by said shaft, a shaft driven by the reduction gear, and a power storage device, likewise carried by said framework operatively connected with the second-named shaft and adapted to accumulate energy from the unwinding of the music roll to automatically rewind the latter, the reduction gear, the power storage device and both shafts being removable with said framework bodily, as a unit, from the instrument.

2. Improved mechanism for automatically rewinding the music rolls of player pianos and the like, consisting in the combination, with a music roll spindle having a sprocket wheel thereon and uprights near each end of said spindle, of a removable framework comprising a horizontal member and depending legs adapted to rest upon said uprights, a reduction gear supported on said framework and driven from said sprocket wheel, a governor associated with the reduction gear, and a power storage device driven by said reduction gear and adapted to accumulate energy from the unwinding of the music roll to automatically rewind the latter.

3. Improved mechanism for automatically rewinding the music rolls of player pianos and the like, consisting in the combination of a reduction gear operatively connected with the music roll spindle, a power storage device actuated through the reduction gear and adapted to accumulate energy from the music roll unwinding operation to automatically rewind said roll, and a stop mechanism associated with said power storage device.

said stop mechanism comprising a member rotated by the power storage device during the rewinding operation and means to limit such rotation of said member.

5 4. Improved mechanism for automatically rewinding the music rolls of player pianos and the like, consisting in the combination of a reduction gear operatively connected with the music roll spindle, a power storage 10 device driven through the reduction gear and adapted to accumulate energy from the music roll unwinding operation to automatically rewind said roll, and a stop mechanism associated with said power storage 15 device and comprising a stop wheel driven through the reduction gear, a moving limit stop carried by said wheel and a stationary limit stop adapted to be engaged by said moving limit stop to limit the rotation of 20 the stop wheel.

5 5. Improved mechanism for automatically rewinding the music rolls of player pianos and the like, consisting in the combination of a reduction gear operatively connected 25 with the music roll spindle, a power storage device operated through the reduction gear and adapted to accumulate energy from the music roll unwinding operation to automatically rewind said roll, and a stop mechanism associated with said power storage 30 device and comprising a stop wheel driven through the reduction gear, a moving limit stop freely mounted in an arcuate slotway in said wheel and a stationary stop or member 35 adapted to be engaged by said moving stop to limit the rotation of the stop wheel and to permit the latter to overrun the moving stop after its engagement with the stationary stop.

40 6. Improved mechanism for automatically rewinding the music rolls of player pianos and the like, consisting in the combination of a shaft driven from the music roll spindle, a reduction gear driven by said shaft, a 45 shaft driven by said reduction gear, a power storage device actuated by the second-named shaft and adapted to accumulate energy from the music roll unwinding operation to automatically rewind said roll, and a stop 50 mechanism associated with said power storage device, said stop mechanism including a stop wheel mounted on the second-named shaft and provided with an arcuate slotway, a moving limit stop freely mounted in said 55 slotway and a stationary stop adapted to be engaged by said moving stop whereby the rotation of the stop wheel is limited and said wheel is permitted to overrun the moving stop after its engagement with the stationary stop.

65 7. Improved mechanism for automatically rewinding the music rolls of player pianos and the like, consisting in the combination of a framework adapted to rest within the upper part of the instrument, a shaft carried

by said framework, a sprocket wheel carried by said shaft and driven from the music roll spindle, a reduction gear carried by said framework and driven by said shaft, a shaft driven by the reduction gear, a power 70 storage device mounted on the second-named shaft and adapted to accumulate energy from the music roll unwinding operation to automatically rewind said roll, and a stop mechanism associated with the power storage device and comprising a pair of opposite discs mounted in spaced relationship upon the second-named shaft and having opposite arcuate slotways, a moving limit stop extending between said discs and mounted to 75 slide freely in said slotways and a stationary limit stop disposed between said discs and adapted to be engaged by said moving stop.

8. Improved mechanism for automatically rewinding the music rolls of player pianos and the like, consisting in the combination of a reduction gear driven from the music roll spindle, a coiled spring adapted to be wound up by the reduction gear during the unwinding of the music roll and to automatically rewind said roll during the unwinding or expansion of the spring, and means operative automatically upon said spring to prevent complete unwinding thereof when the music roll is rewound, for the 90 purpose set forth.

9. Improved mechanism for automatically rewinding the music rolls of player pianos and the like, consisting in the combination of a reduction gear driven from the music roll spindle, a coiled spring adapted to be wound up by the reduction gear on the unwinding of the music roll and to automatically rewind said roll on the unwinding or expansion of the spring, and a stop mechanism associated with said spring and comprising a member rotated by the spring during its expansion and means to limit such rotation of said member before the spring 100 has been completely expanded whereby the unwinding of the spring is limited, for the purpose set forth.

10. Improved mechanism for automatically rewinding the music rolls of player pianos and the like, consisting in the combination of a reduction gear driven from the music roll spindle, a coiled spring adapted to be wound up by the reduction gear on the unwinding of the music roll and to automatically rewind said roll on the unwinding or expansion of the spring, and a stop mechanism associated with said spring and comprising a rotary member having an arcuate slot therein, a moving stop freely mounted in said slot and a stationary stop adapted to be engaged by said moving stop whereby the unwinding of the spring is limited, for the purpose specified.

11. Improved mechanism for automatically rewinding the music rolls of player

pianos and the like, consisting in the combination of a reduction gear driven from the music roll spindle, a coiled spring adapted to be wound up by the reduction gear on the 5 unwinding of the music roll and to automatically rewind said roll on the unwinding or expansion of the spring, a stop wheel operatively connected with said spring, a moving stop carried by said stop wheel and 10 adapted to move circumferentially thereof, and a stationary member adapted to engage said moving stop, for the purpose set forth.

12. Improved mechanism for automatically rewinding the music rolls of player 15 pianos and the like, consisting in the combination of a reduction gear driven from the music roll spindle, a coiled spring adapted to be wound up by the reduction gear on the unwinding of the music roll and to automatically rewind said roll on the unwinding or expansion of the spring, a stop wheel operatively connected with said spring and 20 having an arcuate slot, a moving stop mounted to slide in said slot, and a co- 25 operating stationary stop adapted to be engaged by said moving stop whereby the unwinding of the spring is limited on the rotation of the stop wheel in one direction and said wheel is permitted to over-run the mov-

ing stop thereon when the stop wheel is rotated in the opposite direction, for the purpose set forth. 30

13. Improved mechanism for automatically rewinding the music rolls of player 35 pianos and the like, consisting in the combination of a shaft, a sprocket wheel carried by said shaft and operatively connected with the music roll spindle, a reduction gear driven by said shaft, a shaft driven by the reduction gear, a coiled spring connected at 40 one end to the second-named shaft and adapted to be wound up through the reduction gear on the unwinding of the music roll and to automatically rewind the music roll on the unwinding or expansion of the 45 spring, a stop wheel mounted on said second-named shaft, a moving stop carried by said stop wheel and adapted to slide circumferentially thereof, and a stationary stop adapted to be engaged alternatively on opposite sides by said moving stop as the stop 50 wheel rotates in opposite directions, for the purpose set forth.

In testimony whereof I affix my signature.

J. L. SCOTT.
